UNITED STATES PATENT OFFICE.

VANDIVER J. VAN HORN, OF CHICAGO, ILLINOIS, ASSIGNOR TO UNION SPECIAL MACHINE COMPANY, OF CHICAGO, ILLINOIS, A CORPORATION OF ILLINOIS.

ORNAMENTAL SEAM FOR SEWED ARTICLES.

1,100,509.

Specification of Letters Patent. Patented June 16, 1914.

Application filed February 13, 1911. Serial No. 608,379.

To all whom it may concern:

Be it known that I, VANDIVER J. VAN HORN, a citizen of the United States, residing at Chicago, in the county of Cook, 5 State of Illinois, have invented certain new and useful Improvements in Ornamental Seams for Sewed Articles, of which the following is a description, reference being had to the accompanying drawing and to the 10 letters and figures of reference marked thereon.

My invention relates to new and useful improvements in ornamental seams for sewed articles.

15 An object of the invention is to provide a fabric with a plurality of substantially parallel lines of stitching and also an ornamental thread formed into loops which are so disposed relative to the lines of stitching 20 as to form an ornamental seam.

In the drawings:—Figure 1 is a plan view of a seam made in accordance with my invention. Fig. 2 is an enlarged diagrammatic view showing more clearly the construction of my seam.

The fabric 1 is provided with a plurality of lines of stitching 2 and 3, which are substantially parallel throughout the extent of the seam. In Fig. 2 the needle punctures in 30 the line of stitching 2, are indicated at 4, while the needle punctures in the line of stitching 3 are indicated at 5.

An ornamental thread 6, extends along the line of stitching 3, and at intervals is 35 formed into loops 7, 7. The loops are similar in construction and pass underneath the thread 8 in the line of stitching 3 between consecutive needle punctures. The loop 7, extends across the seam and underneath the 40 thread 9, extending between consecutive needle punctures 4, 4. After being passed under the thread 9, said loop is bent as at 10, so as to lie substantially parallel with the line of stitching 2. In the present embodiment of my invention, said loop is

opened out so as to receive two needle punctures 4, 4, in the line of stitching 2. The length of the bent portion of the loop is somewhat shorter than the distance between the bases of the adjacent loops 7, 7, so as 50 to leave a space between the end of the loop and the adjacent loop.

Having thus particularly described my invention, what I claim as new and desire to secure by Letters Patent is:—

1. An ornamental seam for sewed articles including a plurality of parallel lines of stitching, and an ornamental thread extending along one of said lines of stitching, said ornamental thread being formed into loops 60 at intervals separated by a plurality of stitches which loops extend from one line of stitching to another, said loops being bent at said last named line of stitching where they are secured by said line of 65 stitching.

2. An ornamental seam for sewed articles, including two parallel lines of stitching and an ornamental thread extending along one of said lines of stitching, said thread at intervals separated by a plurality of stitches being formed into loops passing under the thread joining consecutive needle punctures in one line of stitching and under the thread joining consecutive needle punctures in the 75 other line of stitching, said loops being bent at said last named line of stitching to follow the lines of stitching where they are secured by said line of stitching, the portion of the loops lying, in the line of stitching, 80 being of less length than the distance between the bases of said loops, whereby a space is formed between the end of the loop and the adjacent loop.

In testimony whereof I affix my signature, 85 in presence of two witnesses.

VANDIVER J. VAN HORN.
